UNITED STATES PATENT OFFICE.

LUDWELL H. GILMER, OF PHILADELPHIA, PENNSYLVANIA.

COLLAR.

Application filed July 27, 1922. Serial No. 577,817.

This invention is a collar having a tab fixed on an end thereof and adapted for engaging a necktie to hold it in position, particularly a tab attached to one end of the neckband of a turn-down collar below the upper edge of such end and so as to be covered by the turn-down part thereof.

In the accompanying drawing, Fig. 1 is a view of a turn-down collar provided with the tab of my invention, the collar being expanded so that the neckband and turn-down part lie in a common plane; Fig. 2 is a perspective view of the collar illustrated in Fig. 1, the neckband and turn-down part being folded together with a corner of the turn-down part deflected to show the tab, and Fig. 3 is a view similar to that shown in Fig. 2 with a necktie combined with the collar and engaged by the tab.

As illustrated in the drawings, a collar comprising the neckband 1 and the turn-down part 2 is provided on the end 1' of the neckband with a tab 3 extending downwardly from the top thereof and fixed to the band by sewing the parts together so that the tab shall be hinged on the line 4—4 parallel to the top of the neckband, the bottom of the tab being adapted to be deflected outwardly. When the collar is folded and the ends brought together as illustrated in Figs. 2 and 3 the tab will be covered by the turn-down part in its normal position. The sec-

tion 5 of the necktie, which lies between the parts 1 and 2, is engaged under the tab 3 and thereby prevented from rising, the knot 5' of the tie being prevented by the tab from moving out of its symmetrical relation to the collar.

Having described my invention, I claim:

1. A fold-over collar comprising a neckband and a fold-over wing, end portions of said band extending past the ends of said wing, and a tie-engaging tab secured to and depending from the upper edge of one of said end portions.

2. A collar comprising a neck-band and a fold-over wing, end-portions of said band extending past the ends of said wing, and a tie-engaging tab secured to and depending from the upper edge of one of said end-portions adjacent the free end thereof.

3. A collar comprising a neck-band, a fold-over wing secured centrally to said band, end-portions of said band extending past the ends of said wing and adapted to be secured in position on the collar-band of a shirt in overlapped relation, and a tie-engaging tab secured to and depending from the upper edge of the overlapping end of the band.

In testimony whereof I have hereunto set my name this 19th day of July, 1922.

LUDWELL H. GILMER.
